Patented Dec. 17, 1974

233,931

ULTRASONIC INTRUSION ALARM

Ralph W. Goble, Eldora, and Kenneth R. Hackett,
Boulder, Colo., assignors to Sontrix, Inc., Boulder,
Colo.

Filed Dec. 21, 1972, Ser. No. 317,267

Term of patent 14 years

Int. Cl. D29—99

U.S. Cl. D10—106

FIG. 2

FIG. 3

FIG. 1

FIG. 4

FIG. 5

FIG. 1 is a perspective view of the ultrasonic intrusion alarm showing our new design;

FIG. 2 is a top plan view thereof;

FIG. 3 is a side view thereof;

FIG. 4 is a bottom end view thereof, the opposite end being a mirror image thereof; and

FIG. 5 is a bottom view thereof.

We claim:

The ornamental design for the ultrasonic intrusion alarm, as shown and described.
